BRACELET OR SIMILAR ARTICLE

Olof V. Anderson, Forge Road, North Kingston, R.I.

Filed Sept. 10, 1964, Ser. No. 31,663

Term of patent 14 years

(Cl. D45—4)

FIG. 1

FIG. 2

FIG. 3

FIGURE 1 is a top plan view of a bracelet or similar article, showing my new design, portions thereof being shown broken away to indicate indeterminate length.

The essential features of the design reside in the full line portions and consist primarily in the interlocking links oval in side elevation and V-shaped in plan view with a cross bar fastened to the narrow portion of each succeeding link, all as shown on the drawing.

I claim:

The ornamental design for a bracelet or similar article, as shown and described.
